 The Fyr-Fyter Company, a corporation of Delaware
 Filed Mar. 7, 1963, Ser. No. 263,501
 5 Claims. (Cl. 251—43)

The present invention relates to fire extinguishing apparatus, and more particularly to an improved discharge valve for fire extinguishing fluid.

In fire extinguishing apparatus it generally is desirable that the discharge valves for the fire extinguishing fluid operate with low energy requirements in order that the control equipment be as light in weight as possible. In the event the fire extinguishing fluid is carbon dioxide it is at comparatively high pressure at room temperature, and in order to be discharged at a high rate, it must be confined by a discharge valve of large discharge area requiring a large operating force. Such discharge valves are generally pressure operated and controlled by pilot valves which release fluid from the container to actuate the pistons to unseat the main valves. In order that the main valve be held open until the container has been completely discharged mechanical latching means has been used. Such a construction is described in U.S. Patent 2,622,612 issued to A. Manhartberger on December 23, 1952, for a Pilot Operated Valve with Automatic Holding Means. This patent discloses a construction utilizing locking balls adapted to pass into openings in a locking sleeve when the pilot valve is operated.

The present invention aims to provide a fire extinguisher discharge valve with pneumatic locking means for maintaining the main valve unseated until the pressure of the fire extinguishing fluid has dropped below a predetermined value.

In accordance with the invention this is accomplished by providing a fire extinguisher valve in which piston means is integral with the main valve member, a pilot or check valve being provided to release fluid from behind the piston so that pressure against the front of the piston causes it to move the main valve into the open position. Fluid blocking means is provided operative by movement of the check valve so that the piston valve member is locked in open position by pressure against the front of the piston. Upon the discharge of the fire extinguishing fluid and the dropping of pressure against the front of the piston the valve is again closed by spring action.

The construction is advantageous in that upon discharge the main valve member is pneumatically locked in the open position even though the pilot or vent valve is only momentarily opened and is closed thereafter, further, the extinguisher may be charged through its outlet.

Another object of the invention is to provide a fire extinguisher discharge valve which is simple and economical in manufacture, efficient in operation and durable in use.

Other objects and advantages of the invention will be apparent from the following description and from the accompanying drawing which shows, by way of example, an embodiment of the invention.

The drawing is a sectional view through a fire extinguisher discharge valve in accordance with the invention, portions of the control head bushing and of the discharge outlet being broken away.

Referring to the drawing there is shown in the figure a fire extinguisher valve 1 in accordance with the invention and including a housing 2 having a threaded lower end 3 adapted to be threadedly received in the neck of a fire extinguisher container. An inlet passage 4 is adapted to threadedly receive a siphon tube as is well known in the art.

2

The discharge valve is provided with a threaded outer surface 5 to receive a discharge line fitting. A conventional safety fitting 6 is provided in the outlet and adapted to be moved inwardly by the conduit so as to be rendered inoperative when the discharge line is connected to the valve, the function of the safety means 6 being well known in the art and not forming part of the present invention. A partition member 9 provided with a valve seat 10 separates the inlet portion 4 and the outlet portion 11 of the valve.

The housing 2 is fitted with a safety plug 12 including a safety disc 14 as is well known in the art, the safety disc closing the inlet passage 4 from the atmosphere. A conventional control head may be attached to a boss 15 extending from the housing 2, the threaded portion being shown as broken away. A piston valve member 16 includes a valve member 17 fitted with seating material 19 adapted to engage the valve seat 10. Integral with the valve member 17 is the piston portion 20 having a front face generally indicated at 21 and a rear face indicated at 22. The housing is formed with a cylinder 24 for the reciprocation of the piston valve member 16.

The piston valve member 16 is made with face 21 and its rear face 22 both larger in area than the area of the valve seat 10. The piston valve member 20 is provided with a recess 25 on its rear side for the reciprocation therein of an extension 26 of a pilot or check valve 27 also fitted with seating material 29 and adapted to engage a valve seat 30 positioned about a vent valve opening 31 located in a partition member 32 closing one end of the cylinder 24. A spring 33 abuts at one end against the main valve member 17 and at its other end against the check valve member 27 tending to urge both valve members against their respective seats.

In order to pass fluid from the front face to the rear face of the piston valve member 16, a fluid passage 34 is provided extending from the inlet passage 4 to the recess 25 in the piston. Fluid flow limiting means are provided at 35 by reducing the diameter of the passage 34. In an operative embodiment of the invention the passage 34 is of a diameter of .093 inch while the reduced portion is of the order of .031 inch in diameter. The fluid passage from the recess 25 to the face 22 of the piston valve member is provided by means of openings 36 and 37 extending through the extension 26 of the check valve member. In a working embodiment of the invention the openings 36 and 37 have been made of the order of .046 inch in diameter. In this construction the valve seat 10 was approximately one-half inch in diameter while the piston valve member 16 was one inch in diameter.

Means are provided to close off the fluid passage leading from the front face 31 to the rear face 22 of the piston valve member. Such means includes an O-ring 39 positioned in a groove extending about the wall of the recess 25 of the piston valve member. The O-ring 39 is positioned near the face 22 of the piston valve member in order that when operated the check valve member 20 need only have relative movement with respect to the piston valve member 16 so that the openings 36 and 37 are moved inwardly of the O-ring 39 and thus close off fluid passage to the rear of the piston. An O-ring 40 is positioned about the piston member 16 in a suitable groove so as to seal the space between the outer wall of the piston and the cylinder.

In the operation of the discharge valve 1 it is attached to a container which may be charged by attaching a supply line to the outlet fitting 5. The pressure of the incoming fluid unseats the main valve member 17 and the incoming fluid passes between the valve seat 10 and the seating material 19. The piston valve member 16 does not move inwardly away from its seat a sufficient distance so that the O-ring 39 blocks the passages 36 and

37 and thus the space adjacent the back face 22 is pressurized at the same time as the container is filled so that the main valve member 17 returns to its seat as soon as the charging pressure is dropped in the outlet.

Upon the discharge of the valve by an unseating of the check valve 27 the fluid pressure against the rear face 22 of the piston is almost immediately vented to the atmosphere through the vent passage 31, whereupon the pressure against the front face 21 of the piston valve member 16 causes the piston valve member to move to the right thereby unseating the main valve member 17. Simultaneously the O-ring 39 has passed the openings 36 and 37 thereby blocking the passage of further fluid into the space adjacent the rear face 22 of the piston valve member so that it is pneumatically locked into the open position until the pressure within the inlet drops thus allowing the spring 33 to move both valve members against their seats returning the unit to its initial position. It should be noted that the openings 36 and 37 are of larger area than the metering orifice 35 so that the pressure within the recess 25 is reduced at a faster rate than it is built up by pressure in the inlet 4. The construction is such that the piston valve member 16 will be held pneumatically locked in the open position even though the check or vent valve 27 is closed after actuation. The piston valve member 16 will remain open until the pressure within the valve has dropped so that the force of the spring 33 is able to move both of the valves back against their seats.

While the invention has been described and illustrated with respect to a specific embodiment thereof, it will be understood that other embodiments may be resorted to without departing from the invention. Therefore, the form of the invention set out above should be considered as illustrative and not as limiting the scope of the following claims.

We claim:

1. A fire extinguisher discharge valve comprising a housing having an inlet and an outlet and a fluid passage therebetween, a main valve seat defining inlet and outlet portions of the fluid passage, a valve member adapted to engage the valve seat from the inlet side, a double faced piston member integral with the valve member, the valve member forming part of the front of the piston member, cylinder means in the housing on the inlet side of said seat, said piston sealingly and slidably mounted in the cylinder for movement of the valve member against and away from its seat, the piston having front and rear faces, the areas of each face of the piston greater than the area of the valve seat and the rear face having a greater area than the front face, said piston having an axial recess in its rear face, pressure equalizing fluid passage means leading from the front face of the piston to the rear face thereof through said piston and recess so that the piston is normally urged into valve closing position by the pressure of fluid in its inlet passage, vent means, in the end of the cylinder for venting pressure from the cylinder behind the piston, a valve seat about the vent means, a normally closed vent valve member within the cylinder engaging the valve seat and adapted to be opened to release pressure

5 from the rear face of the piston so that the main valve member is opened responsive to inlet pressure on the front face of the piston, fluid passage limiting means having a smaller passage than said vent means in said fluid passage means leading from the front to the rear faces of the piston so that fluid may be bled from the rear face of the piston through the vent valve at a faster rate than it enters from the inlet, an extension for the vent valve member extending axially inwardly of the cylinder and having a portion thereof slidably engaged in the piston recess, said fluid passage means including a fluid passageway through said extension, and means rendering said last mentioned means ineffective when either of the valve members are unseated.

2. A fire extinguisher discharge valve according to claim 1 in which the cylinder means has an enlarged portion at the valve end of the piston member and said fluid passage limiting means is a metering orifice located in the valve end of the piston member so that the orifice member is unblocked irrespective of the position of the piston member.

3. A fire extinguisher discharge valve according to claim 2 in which the means rendering the fluid passage ineffective when either of the valve members are unseated is an opening forming said fluid passage extending through said vent valve member portion, said portion sealingly and slidably engaged in the piston recess, said opening located outwardly of the piston recess immediately adjacent the rear face of the piston when both valves are seated so that when either of the valve members are unseated said opening is closed by the wall of said recess.

4. A fire extinguisher discharge valve according to claim 1 in which the means rendering the fluid passage ineffective when either of the valve members are unseated is an opening forming said fluid passage extending through said vent valve member portion, said portion sealingly and slidably engaged in the piston recess, said opening located outwardly of the piston recess immediately adjacent the rear face of the piston when both valves are seated so that when either of the valve members are unseated said opening is closed by the wall of said recess.

5. A fire extinguisher discharge valve according to claim 1 in which said vent valve member portion slidably engaged in the piston recess has a recess on its end opposite said vent valve member and a spring is positioned with one of its ends in said recess and its other end abutting against the inner end of the valve member.
